FREE SPRING METAL REED

Filed March 7, 1938

FIG. 1.

UNITED STATES PATENT OFFICE

2,172,972

FREE SPRING METAL REED

James S. Hall, Methuen, Mass., assignor to Emmons Loom Harness Company, Lawrence, Mass., a corporation of Massachusetts

Application March 7, 1938, Serial No. 194,340

3 Claims. (Cl. 139—192)

This invention relates to loom reeds of the type where metal dents are accurately held at the ends in parallel relationship, with spaces between for the warp threads, known in the trade as metal reeds as distinguished from the wood and thread type known more or less as pitch back reeds.

The particular purpose of this invention is to provide a reed made entirely of metal but in which the dents are firmly but resiliently held at their ends so that they will yield sideways to permit a slab or other bunch to pass but will spring back into place after it has passed. My construction also minimizes or softens the effect of vibration on the dents.

15 It consists substantially of dents of the usual flat type which are held together for a short distance from their top and bottom ends by solder between their flat faces and by a strip of metal of a special shape at their front and back edges. These strips may merely engage the edges of the dents or they may be held to the faces and edges of the ends of the dents by solder. Each strip extends inward and is bent at its margin in such a curve that it holds a free coiled 20 spring in place. This coiled spring is not soldered and is not fastened to anything but is kept in position by the curved margins of the strips and by two segmental rods.

This construction allows the use of simple 25 headers which are rigidly fastened to and between the sets of top strips and of bottom strips at each end by solder and rivets or either of them or they may be merely soldered to the dents if removable strips or a removable strip is used. By 30 using free springs of wire having a diameter less than the spaces between the dents, the dents can bend sideways and also twist somewhat but will always be brought back to their correct position.

I am aware that the attempt has been made to 35 hold dents rigidly at their ends and, along parallel lines inside the ends, at the top and bottom, to provide cushioning means of string or cord of textile or other fibres. I am aware that rubber has been used as a cushioning means and 40 I am aware that the usual construction of reeds provides for coils of wire, which are not necessarily springs, for holding the dents in position while the reed is being assembled and soldered. Most of such assembling coils are removed and 45 do not appear in the finished reed but some are permanently attached to the dents or to other parts by solder which is flowed in between their turns. Such soldering removes a great deal of the elasticity of the coil and prevents the turns 50 from moving to and from each other with any

movement of the dents. They are fixed and rigidly held in place.

I believe I am the first to provide a reed in which the dents are rigidly held at their ends but are helped to be resilient by loose springs 5 positioned near to and parallel with the ends of the dents and the holding strips as a permanent part of the reed. As such springs are not soldered and are not otherwise fastened to the dents nor to any other part of the reed, I hold 10 them loosely in place by specially made top and bottom holding strips so that they cannot slip out of place.

In the drawing,

Fig. 1 is an end elevation of a reed of my construction with parts broken away.

Fig. 2 is an enlarged plan view of one end of a reed such as shown in Fig. 1.

Fig. 3 is an enlarged end elevation of part of a reed as from the left of Fig. 1.

Fig. 4 is an enlarged sectional view on the line 4—4 of Fig. 1.

Fig. 5 is an enlarged sectional view on the line 5—5 of Fig. 1.

Fig. 6 is an enlarged end view similar to Fig. 3 25 but with different parts broken away to show the construction.

Fig. 7 is an isometric view of part of the top 30 end of a reed with the spring holding means slid partly off.

Fig. 8 is an end elevation similar to Fig. 3 of a modification.

In the drawing, D represents the dents which, as shown, are of the usual shape. Each dent has an end such as 1 and 2, together with flat faces 35 3, 3 and edges 4, 4.

A, A represent flat strips of metal, 10 representing the flat part, 11 the outer edge, 13 the inner edge and 12 the inner margin which in this case is curved outwardly so as to encircle 40 and confine that portion of a spring S which projects beyond the edges 4, 4 of the dents D.

R, R represents segmental rods of which there are four. Each rod is passed between the edges of the dents and inside the turns of a spring S 45 whereby the springs are prevented from slipping out of place.

B represents solder which is flowed in between the ends of the dents to a distance equal to the flat part of the strips A, this solder going in between the flat part 3 of the ends of the dents at 46 and extending out at 40 so that it reaches and holds the flat part 10 of each strip A rigidly in place with the ends of the dents.

The curved inner margin 12 of each strip A 55

extends over part of each spring S so that while each spring can yield in the direction of the length of the reed, it cannot slip down nor out of place.

5 In Figs. 1, 2 and 5, H represents a header made of a flat strip equal in thickness to the width of the flat face of a dent and of a suitable width to give strength and stiffness to the reed. In the construction shown, in Figs. 1 to 5, each end of each header H is shown as held between the ends of the flat part 10 of the strips A, A by solder at 42 and between its edge and the adjoining dent by solder at 41. As shown, each header is also held in place at each end by a rivet 9.

10 Each header also preferably has near each end at the outside a recess 14, and the ends such as 44 of some or all of the rods R, R are bent at right angles into such a recess so that they will not slip out and so that they help to strengthen the construction of the assembly.

15 These rods R, R may also be soldered on each side of a header H by solder 43.

20 In the construction just described, all of the parts may be soldered together except the free springs S, S.

25 In the constructions shown in Figs. 6 and 7, however, the solder F extends only between adjoining flat faces of the dents, G, G near their outer ends 5 inward to about the line 6. The solder is removed at the ends and edges of the dents so that they are substantially smooth and free of irregularities.

30 There is a free spring such as 7 near the top and bottom and through this extend the segmental rods 8, 8 which correspond with the rods R, R.

35 For spring holding means, in place of the flat strips A, A soldered to the dents and to the headers, I use bent strips such as C, each having a middle part 25, flat parts 20 and 21 and the outwardly curved inner margins 22 and 23 which enclose springs 7 and rods 8, 8.

40 In this construction, as shown in Fig. 6, the headers such as L are fixed in place only by the solder F at 45. The spring holding means C, as shown in Fig. 7, can be slipped on and off, the loose springs such as 7 can be removed if desired. If desired, I can use near each end of the dents two or more free springs 30 and 31 with two sets of rods 32, 32 and 33, 33, as shown in Fig. 8, and I can make the free spring holding means or strip K with two outwardly curved margins 34, 34 and 35, 35 on each side.

45 In Figs. 6 and 7, the end 47 of one of the rods 8 is bent into a recess 48 in each header L.

50 As shown in Figs. 1 to 5, the end of a rod such as R can be bent into a recess and soldered or, as in Figs. 6 and 7, it may be merely bent or in any of the constructions, as, for instance, in Fig. 8, there may be no recess in a header such as M, the rods 32 or 33 being neither bent nor soldered. In fact, the four segmental rods, such as R, can be entirely omitted or can be 55 removed after assembly, especially in the con-

struction shown in Figs. 1, 2, 3, 4 and 5, where the free spring holding means, namely, the strips A, A, are permanently soldered on each side of the ends of the dents.

I claim:

5 1. The combination in a loom reed of a row of parallel dents accurately spaced at equal pre-determined distances from each other and soldered together at each end; with two free coiled metal springs each extending parallel with 10 and inside the soldered ends of the dents; four segmental rods, each passed between the edges of the dents and the turns of a spring; free spring holding means along the edges of the dents at each end, each including a set of two 15 flat holding strips, each with an outwardly curved inside margin which encircles and confines one side of the coils of a free spring, the flat part of each strip of each set being held in place along the ends of the dents near their ends by 20 the solder between the end faces of adjoining dents, such solder also holding the ends of the dents together and to the flat part of the adjoining strips.

2. The combination in a loom reed of a row 25 of parallel dents accurately spaced at pre-determined distances from each other and soldered together at each end; a metal header at the end of each row, each header being substantially as thick as the width of a dent and each having 30 at the outside a rod recess; with two free coiled metal springs, each extending parallel with the inside of the soldered ends of the dents; four segmental rods, each passed between the edges of the dents and the turns of a spring, one end 35 of each rod being bent into a header recess; free spring holding means along the edges near each end of the dents, each including a set of two flat holding strips, each with an outwardly curved inside margin which encircles and confines one side of the coils of a free spring, the flat part of each strip of each set being held in place along the ends of the dents near their ends by the solder between the end faces of adjoining dents, such solder also holding the ends of the dents together and to the flat part of the 40 adjoining strips.

3. The combination in a loom reed of a row of parallel dents accurately spaced at equal pre-determined distances from each other and 50 soldered together at each end; with two free coiled metal springs each extending parallel with and inside the soldered ends of the dents; free spring holding means along the edges of the dents at each end, each including a set of two 55 flat holding strips, each with an outwardly curved inside margin which encircles and confines one side of the coils of a free spring, the flat part of each strip of each set being held in place along the ends of the dents near their ends by the 60 solder between the end faces of adjoining dents, such solder also holding the ends of the dents together and to the flat part of the adjoining strips.

JAMES S. HALL.
